ADJUSTABLE OIL BURNER FOR GARDENS
AND ORCHARDS

Seichi Yoshinaka, Mesa, Wash.

Application April 28, 1937, Serial No. 139,558

2 Claims. (Cl. 158—91)

This invention relates to oil burning heaters for orchards and vegetable gardens.

In the raising of fruit and vegetables where frost occurs, it is frequently necessary at certain seasons, to provide heat for the prevention of damage to such crops by freezing. Various devices have been tried for that purpose, but they have not been satisfactory, or adaptable for producing both smoke, and clean warm vapor. All such devices have also been too expensive in construction for general use in locations where large numbers of heating devices are necessary to protect growing crops of one owner.

It is therefore among the objects of this invention to provide a simple and inexpensive device, and one which can be constructed principally from parts readily obtained in ordinary commercial stores, for burning low grade oils. Such heaters to be adaptable for economical use in large numbers for protecting fruits and vegetables from unseasonable frosts.

A further object is to provide an adjustable heater, for supplying heat to various elevations, and for directing the currents of heat and smoke in predetermined directions.

A still further object is to provide a heater for the formation and dispensing of either heavy smoke and smudges as coverings and/or clean warm vapors, for radiation of warmth over vegetable growths.

With these and other objects that will hereinafter appear, I have illustratively exemplified my invention by the accompanying drawing, of which:

35 Figure 1 represents a perspective view of the assembled burner with parts broken away,

Figure 2 represents an enlarged top plan of a cup for burning oil, with an adjustable cap thereon provided with vanes for directing air currents, 40 and lobes for covering air holes,

Figure 3 represents an enlarged sectional view of the cup and vanes with lobes thereon in position for uncovering air inlet holes,

Figure 4 represents an enlarged fragmentary sectional view of the cup, showing the cap, vanes and lobes in position for covering the air inlet holes,

Figure 5 is a fragmentary view of the upper portion of a burner flue showing a damper plate and assembly therefor, with dotted lines showing an alternate position for the plate.

Like numerals on the different figures represent like parts. Numeral 10 indicates a tubular flue, which may be formed of a section of ordinary stove pipe of desired diameter, or of any

cheaply constructed tubing. The lower end is preferably slit to provide a plurality of legs 11 for use in maintaining the tube in perpendicular position, and in event the use is on soft or cultivated soil, the legs should be adapted to be forced deeply into the earth for rigidity. Entrances 12 for air are provided between the legs and in event of the use of stove pipe or other ready constructed tube, then the alternative sections 13 between the legs are preferably bent inward to provide a flange or bracket 13' around the inside of the tube to support an oil cup 15.

Said cup is preferably provided with a flange 16 around the top thereof, both for supporting the cup and for closing the tube at that point, 15 and it may be integral with the material from which the cup is depressed. Near the lower part of the cup a series of relatively small holes 17 are disposed through the walls thereof and spaced above the bottom of the cup to leave a cavity 15' for receiving and burning fuel oils therein.

An oil supply chamber 18 is suitably positioned adjacent the outside of the tube and is connected with the cup by a feed pipe 19, passed through the tube wall, and is preferably provided with a valve 20 for regulating the flow of oil from the chamber into the cup.

Sufficient air flows into the cup through the small holes to provide for slow combustion of the oil and to thereby produce a heavy smoke or smudge, which is frequently preferred for application on orchard trees, and requires very little oil. In order to carry this smoke to a higher level than the length of one tube or section illustrated at 10, I provide one or more other tubes as 21 slightly larger for slidable or telescopic mounting over the tubes 10, and adapted to be sustained at any desired elevation by a small rod 22 adjustably disposed through any of a series 40 of small holes 23 in opposite sides of the tubes, and resting across the top of the tube 10.

A damper plate 24, is preferably provided over the top of the tube, for regulating the outer flow of smoke and vapor, for various degrees of opening and for guiding the flow in direction desired. For these purposes the plate 24 is preferably pivotally mounted on a pin 25 and supported on a shoulder 26 of an arm 27. The arm in turn is adjustably supported over the tube by resilient fingers 28 and 29 for clamping disposition astride one side wall of the flue. This mounting permits the damper to be moved laterally, and perpendicularly, and obliquely to either side for guid-

ing the flow of smoke and vapor, and for protection against a wind current.

In order to provide for faster consumption of the oil, and for more and cleaner vapor, additional openings 30 through the walls of the cup are provided. These are spaced above the smaller holes, and are relatively larger in diameter, and so provide a greater supply of air, for combustion of the oil and for the combustion of the smoke or carbon, in order to produce a clean heated vapor. This is particularly desired for vegetable gardens, where a sedimentary or sooty deposit on vegetables discolors the same and is objectionable.

15 The directions of the flow of air through the larger holes is regulated by baffle vanes 31, which are attached to, or integral with an annular cap 32, rotatably mounted over the rim of the cup. The vanes slope obliquely downward from the cap, and have flattened faces on planes at right angles with the inner walls of the cup, for directing the flow of air inward and over the flames of the oil for burning the carbon, and upward by spiral travel for increasing the draft upward through the flue. The sizes of the passageways through said larger holes, is controlled by lobes 33, preferably integral with the vanes and suspended on a twist from the lower ends thereof, and have flattened faces on same planes as the inner walls of the cup. Thus when the cap is turned to the position shown in Figure 3 the holes are open, and the air currents are carried over the flames and upward by the vanes. When the cap is turned to position shown in Figure 4, the lobes are positioned across, and close the holes entirely. Other positions of the lobes, may only partially cover the holes, as desired.

In order to adjust or turn this cap and dependent vanes and lobes an aperture or doorway 34, is provided through the wall of the flue 10, adjacent to the top of the cup for entrance of a hand for manual operation, or the insertion of a wire therefor. This aperture is also important for admitting a suitable supply of additional air 45 for inducing or increasing an upward draft through the flues for increasing the flow of smoke or vapor, as may be desired. The extent of the opening through the aperture 34 may be regulated by a door 35 adjustably mounted over the same by a latch bolt 36 affixed through the upper portion of the door and slidably disposed in slot 37 through the wall of the tube. Notches

38 along one side of the slot provide supports for the bolt at such various elevations, for maintaining the door in desired positions for regulating the doorway passage.

I have described generally the functions of the upper end larger holes in the cup, and the accompanying vanes and lobes, as if for creating clean heated vapor, but they are not solely for such purposes. They are also used, and important, for regulating proportions of combined smoke and heat, in varying degrees, for a variety of purposes, according to the temperature of the weather, the velocity of the wind, and the kind of trees, shrubs, and vegetables to be protected thereby.

15 While I have illustrated my invention by specific drawing, and this specification, for explaining the general operation, yet I do not desire to limit my invention thereby, but desire to fully cover the invention within the scope of my claims.

Having described my invention I claim as new,

1. An oil burner for producing heated vapor for orchards and vegetable gardens, comprising, a tubular flue, an oil cup mounted within and across the interior of said flue, and means for feeding a predetermined supply of fuel oil into said cup, said cup provided with holes circularly disposed around and through the side walls thereof, an annular cap rotatably mounted around the rim of said cup, flattened vanes projected downward obliquely from said cap along the inner sides of said walls and comprising two faces—one face parallel with the inner sides of said cup for closing said holes, and the other on a plane on an angle to said walls for directing a flow of heated vapor upward with a gyratory motion for promoting more thorough combustion.

2. An oil burner for producing heated vapor for orchards and vegetable gardens, provided with a cup for receiving and burning oil therein, said cup provided with holes circularly disposed around and through the side walls thereof, an annular cap rotatably mounted around the rim of said cup, flattened vanes projected downward obliquely from said cap along the inner sides of said walls and comprising two faces—one face parallel with the inner sides of said cup for closing said holes, and the other on a plane angularly to said walls for directing a flow of heated vapor from said cup upward by spiral movement for promoting more thorough combustion.

SEICHI YOSHINAKA.
